UNITED STATES PATENT OFFICE.

EMSLIE E. MURRAY, OF SCHENECTADY, NEW YORK.

STEAM PIPE FOR LOCOMOTIVE ENGINES.

Application filed March 31, 1926. Serial No. 98,850.

My invention relates in general to steam locomotives of the type provided with a group of cylinders located to the rear of the front end of the boiler, either to the rear of 5 a standard formed grouping of cylinders or to the rear of a driving wheel system operatively associated with the cylinders, and a general object of the invention is to provide an improved steam pipe structure for delivering steam to such rearwardly located cylinders.

It has been the practice in the installation of steam pipes for the rear cylinder group to provide two separate pipes, one extending 15 along one side of the boiler to feed the cylinders on the same side, and another extending along the other side of the boiler to feed the cylinders on that side. This construction has been open to the objection that 20 it necessitated a duplication of parts with a correspondingly excessive weight, cost of construction, and wastage of valuable space.

In order to do away with the objectionable features referred to I have provided a 25 steam feed pipe structure for the rearward group of cylinders which consists of a single pipe extending along one side of the boiler to the position of the rear cylinders. At this point the pipe is provided with a branch 30 extending beneath the shell of the boiler to the cylinders on the other side.

The improvement claimed is hereinafter fully set forth.

In the accompanying drawings: Figure 1 35 is a side view, in elevation, certain of the parts being diagrammatically indicated, of a compound articulated locomotive, embodying my invention; Fig. 2, a transverse section, on an enlarged scale, taken on the line 40 II, II, of Fig. 1; and, Fig. 3, a plan view, on an enlarged scale, of the branch pipe connection used in my invention.

In the practice of my invention, referring descriptively to the specific embodiment 45 thereof which is herein exemplified, as applied to a steam locomotive of the "Mallet" articulated compound type, a pair of low pressure cylinders, 5, is located in a forward position with relation to the smoke box portion 6, of a boiler 7. A second engine unit including cylinders 8, is mounted to the rear of the forward portion of the boiler 7. The truck 9, which carries forward cylinders 5, has an articulated connection at 10, with the 55 rearward framework 11, which carries the rear cylinders 8 and supports the boiler 7.

With this construction the forward engine unit 5 is free to swing laterally with respect to the boiler, as is characteristic with this type of locomotive.

An important feature of the present invention resides in the means provided for supplying steam to the valve chests 12, of the rear high pressure cylinders 8. This means takes the form of a single steam supply pipe 13, extending along one side of the boiler from the forward end thereof to the position of the rear cylinders 8, the pipe 13 being provided with a branch 14, extending across the space beneath the boiler to provide a steam supply connection with the steam chest 12 on the other side of the locomotive. The single main steam supply pipe 13, which is thus utilized to supply steam to each of the cylinders 8, is formed with a suitable cross-section to carry the double supply of steam thus required, as compared with the volume of steam carried by each of the two separate steam supply pipes heretofore used for this purpose. The branch pipe 14 is reduced in size, as will be apparent, to supply the steam required for one of the two cylinders 8. The branch pipe 14 is provided with a T-head portion 15, which has a ball-joint ring connection 16 with the main steam supply pipe 13, and a similar connection at 17, between the reduced portion 18, of the T-head 15 and an elbow pipe section 19, which forms an inlet connection to the valve chest 12 of the right hand cylinder 8.

The forward end of the lateral or main steam pipe 13 is equipped with a telescopic or slip joint 20, to provide for longitudinal expansion and contraction of the pipe 13, in response to temperature changes which affect the length thereof. The slip joint 20, referred to, is interposed between the forward end of the main steam supply pipe 13 and an elbow 21, which is connected to a branch pipe 22, mounted in and following the curvature of the shell of the smoke box 6, already referred to. The branch pipe 22 connects at its upper end with the header 23 of the super-heater or directly with the main steam supply pipe 24, which leads from the throttle valve 25, mounted in the dome 26. It will thus be seen that but a single supply pipe branch is mounted in the smoke box chamber, in lieu of the two branch supply pipes heretofore employed for that purpose.

While I have referred to a throttle located

in the boiler dome 26; I wish it to be understood that the branch supply pipe 22 may be connected directly to the throttle chamber located in the smoke box to control the flow of steam in the supply pipe after it has passed through the super-heater.

In order to protect the steam pipes 13 and 14 from the cooling action of the atmosphere, they are preferably encased in lagging, formed of any suitable heat insulating material as in standard practice.

It will be seen that by the use of the single longitudinally extending steam supply pipe 13, with a connecting transversely extending branch pipe 14, in the region of the rear cylinder 8, I have succeeded in providing a supply of steam to the two rear cylinders without necessitating the use of two separate steam supply pipes mounted on opposite sides of the boiler shell. I have thus succeeded in avoiding a duplication of parts and have correspondingly decreased the weight of material used, as well as the cost of construction, and, in addition, have provided space on one side of the boiler in which other necessary attachments to the boiler shell can be placed.

I claim as my invention and desire to secure by Letters Patent:

1. In a steam locomotive of the type having cylinders mounted to the rear of the forward end of the boiler, a single steam pipe

line communicating with the throttle chamber and extending downwardly along one side of the smoke box, said pipe line passing through the smoke box shell and extending rearwardly along a lower portion of one side of the boiler shell to supply steam to one of said cylinders, and a branch pipe extending from said line across the space beneath the boiler to supply steam to the cylinder on the other side of the locomotive.

2. In a locomotive comprising a boiler, a smoke box, a group of cylinders mounted to the rear of the forward end of the boiler, each cylinder having a superposed distribution valve chest, one of the cylinders being disposed on each side of the locomotive; a single steam pipe leading down through the smoke box and through the lower portion of a side wall thereof, for supplying steam to all of the valve chests of the group; a single steam pipe connected to the first-mentioned pipe and extending throughout its length along the lower portion of a side of the boiler, to the valve chest on such side; and a branch pipe extending from said second-mentioned pipe, across the boiler, to the valve chest on the opposite side thereof.

Signed at New York, in the county and State of New York, this 26th day of March, 1926.

EMSLIE E. MURRAY.
